Primary Examiner — Darlington Ly(74) *Attorney, Agent, or Firm* — Cantor Colburn LLP(57) **CLAIM**

The ornamental design for a vehicle rail extension, as shown and described.

DESCRIPTION

FIG. 1 is a front perspective view of the vehicle rail extension showing our new design;

FIG. 2 is a rear perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines in the drawings illustrate portions of the vehicle rail extension that forms no part of the claimed design.

1 Claim, 4 Drawing Sheets(56)
